FEEDBACK PHASE MODULATION RECEIVER

Murray G. Crosby, Riverhead, N. Y., assignor to
Radio Corporation of America, a corporation of
Delaware

Application October 7, 1938, Serial No. 233,719

19 Claims. (Cl. 250—20)

This application concerns new and improved phase modulation receivers in which inverse feedback is utilized to reduce the degree of phase modulation applied to the phase modulation detecting system of the receiver. In phase modulation detectors known heretofore the amount of phase deviation which they will handle is limited. My invention provides a phase modulation receiver which has increased capabilities 10 with regard to depth or degree of phase modulation.

In the phase modulation receivers of this disclosure the output voltage from the detecting system is fed back to a phase modulation circuit 15 which precedes the detecting system. Thus, when the incoming wave is phase modulated the voltage resulting from demodulation appearing at the detector output is applied to this phase modulator circuit preceding the detecting system with such a polarity that the effective phase deviation of the modulated wave applied to the detectors is reduced. For a given degree of phase deviation such a reduction of deviation applied to the detecting system will reduce distortion since the maximum demodulation 25 capabilities of the detecting system are not reached.

This same feature may be utilized to allow a higher degree of modulation of the wave to be applied to the receiver to permit a wide-band phase modulation of the wave used in the system. Thus the depth of modulation may be increased at the transmitter so that a noise reduction may be effected. In the receivers of the prior art this reduction has been accomplished 35 by means of frequency division by multivibrators at the receiver as described in my United States application Serial No. 107,336, filed October 24, 1936. The method of the present disclosure allows the use of wide band phase modulation 40 without the use of multivibrators which in some cases are somewhat unstable.

In a modification the potentials from the output of the phase modulated wave demodulator are passed through a circuit which modifies their 45 amplitude so that they vary in amplitude directly in accordance with frequency. These potentials then frequency modulate (instead of phase modulating) the oscillator supplying heterodyne current to the second detector. In this manner the phase deviations on the wave 50 are reduced.

In the several modifications the polarity of the potentials supplied by the detectors to the modulator may be such as to additionally phase modulate the received wave. That is, the de-

gree or depth of phase modulation may be increased if desired as well as decreased.

In describing my invention more in detail reference will be made to the attached drawings; wherein

Figure 1 shows a phase modulated wave receiver with means for unmodulating or further modulating the received wave to thereby control its degree of phase modulation as desired;

Figures 3 and 4 are diagrammatic showings of 10 modifications of the arrangement of Figure 1; while

Figures 2a to 2h are vector diagrams used 15 in illustrating the operation of the detectors of the present invention.

The circuit of Figure 1 shows a specific embodiment of my invention in which neutralizing through coupling tubes, as described in my United States application Serial No. 165,056, filed September 22, 1937, now Patent #2,156,374, issued May 2, 1939, is utilized in the means for converting the phase modulated current to amplitude modulated current for detection.

To simplify the description of the basic principle of my method and means it is assumed 25 that by the use of heterodyning means known in the art and comprising signal pick up means 1, radio frequency amplifying and detecting means 2 and local oscillator 3, phase or amplitude modulated wave energy has been reduced in 30 frequency, amplified in 2 if desired, and is impressed at intermediate frequency on the input electrodes of an amplifying tube 4 and from the output 5 of tube 4 on the grid 7 of a coupling tube 6 from the output electrode 9 of which it is 35 impressed on the primary winding 10 of a transformer 11 having a secondary winding 12. The primary winding 10 is shunted and properly damped by a resistor 18 and tuned by a variable condenser 20. The secondary winding 12 is likewise properly damped by a resistor 19 in shunt thereto and is tuned by a variable condenser 22. By properly adjusting the coupling, tunings, and dampings of this transformer, it is made to have 40 a band pass characteristic so that all of the frequencies of the phase modulated wave are passed thereby uniformly.

The secondary winding 12 has its terminals connected as shown to a piezo electric crystal 30 and a variable capacity 32 which with coupling tube 33 serves as means for neutralizing, under-neutralizing, or over-neutralizing the crystal 30. In this particular case the crystal is over-neutralized by condenser 32 and coupling tube 33. The crystal 30, and capacity 32 con- 50 55

nect the control grids 34 and 36 of electron discharge tubes 31 and 33 to winding 42, as shown, to feed wave energy thereto from 12. The energy passed by the crystal 30 is amplified by 5 the electron discharge tube 31, while the neutralizing energy passed by coupling tube 33 is amplified by the electron discharge tube 33. The anode 38 of tube 31 and the anode 40 of tube 33 are tied together as shown and connected 10 to the tuned primary winding 42 of a transformer 44. The capacity of the holder for the crystal 30 is neutralized, over-neutralized, or under-neutralized as desired by the neutralizing condenser 32 acting through coupling tube 33. 15 The winding 42 is tuned by a condenser 41. The secondary winding 46 of transformer 44, tuned by condenser 47, is connected as shown to the electrodes of a diode rectifier 50. The combination of the current passed by crystal 30 20 and tube 31, and capacity 32 and tube 33 takes place in the primary winding of transformer 44. Resistors 45 and 43 furnish a direct current connection to ground for the grid direct current circuits of tubes 31 and 33 while resistor 49, 25 which is properly by-passed, furnishes self-bias to these tubes.

Modulated current which has been converted from phase modulation to corresponding amplitude modulated current for demodulation purposes is also taken from the terminal of crystal 30 and fed to the control electrode 52 of electron discharge tube 50. This current is passed by a filter which is under- or un-neutralized. The anode 54 of coupling tube 50 is connected 35 to the primary winding 56 of a transformer 58, the secondary winding 59 of which is connected to the electrodes of a diode rectifier 60. Windings 56 and 59 are tuned by condensers 55 and 57 respectively, and a damping resistance 70 is 40 connected with winding 56.

Transformers 17, 44 and 58 are band pass transformers with their tunings and dampings adjusted so that the center of the band passed is substantially equal to the mean frequency of 45 the phase modulated current impressed on winding 10.

The transformer 58 in the plate circuit of tube 50 feeds the un-neutralized crystal energy to diode 60. By adjusting condenser 32 so that an 50 over-neutralized crystal filter characteristic, as to the intermediate frequency phase modulated wave energy, is obtained in transformer 44, detector 50 will be detecting energy passed by said filter of over-neutralized characteristics, where- 55 as detector 60 will be detecting energy passed directly by 30, that is, energy passed by a filter having an unneutralized characteristic.

The diode resistors 61 and 63, which are by- 60 passed by I. F. by-pass condensers as shown, are connected in series so as to differentially combine the detected outputs from the two trans- 65 formers 44, 58. The resulting energy from these two resistors 61 and 63 is, if desired, fed to an automatic frequency control tube (for simplicity 70 not shown here) which in turn may control the tuning of the high frequency oscillator 3 used to convert the received energy to intermediate frequency. A frequency control means as described here has been shown in my United States applica- 75 tions Serial No. 165,056, filed September 22, 1937, now Patent #2,156,374, issued May 2, 1939 and Serial No. 167,344, filed October 5, 1937, now Patent #2,156,375, issued May 2, 1939. Similar control circuits have also been disclosed in my prior United States Patents No. 2,065,565, dated

December 29, 1936; No. 2,085,008, dated June 29, 1937; and application Serial No. 124,967, filed February 10, 1937.

Potentials from the high potential end of 61 are also supplied to the phase modulating or un- 5 modulating means of the present invention. Potentials from 61 and 63 are also fed to an audio frequency amplifier to produce the output char- 10 acteristic of the phase modulations on the re- ceived wave.

In the operation of the receiver of Figure 1 two filter characteristics are produced to be fed to the two diode detectors 50 and 60. The energy fed from the crystal output terminal to amplifier 50 is un-neutralized crystal energy and has a 15 characteristic shown in Figure 2a. This energy appears in transformer 58. The characteristic of the energy present in transformer 44 is as shown in Figure 2e, being derived from a filter of the over-neutralized type such as is obtained by over- 20 neutralizing crystal 30 by means of neutralizing condenser 32. This is obtained by adjusting con- 25 denser 32 so that its capacity is greater than that of the crystal holder which holds crystal 30. These two crystal filter characteristics as shown 26 in Figures 2a and 2e have reactance character- ists as shown in Figures 2b and 2f, respectively.

In the case of Figure 2b a negative reactance 30 is present on both sides of the carrier frequency, that is, the circuit would be capacitive on both 35 sides of the carrier except for the very short in- 40 terval near the carrier frequency. Since the re- actance is capacitive in the frequency region in which the side bands are disposed and is resist- 45ive at the carrier frequency, the phase of the 40 side bands will be shifted 90° with respect to the carrier. In Figure 2c the carrier and side bands of a phase modulated wave are shown. The carrier is marked C, the upper side band U and the lower side band L. The positive direction of 50 rotation is taken as clockwise and the directions of rotation of the side bands with respect to the carrier are indicated by arrows attached to the side band vectors. Side bands of an order greater than 1 have been neglected due to their small 55 amplitude and for simplicity of explanation. When the phase modulated wave of Figure 2c is 50 passed to a filter having the characteristic of Figure 2a and the reactance characteristic of Figure 2b and side bands are shifted 90° with re- 55 spect to the carrier so that the side band rela- 60 tion shown in Figure 2d is effected. With the 65 relation of 2d between the carrier and side bands, the wave is an amplitude modulated wave. There would also be an attenuation of the side- 70 bands which is not shown in Figure 2d. This 75 conversion of the phase modulated wave to an amplitude modulated wave takes place in trans- 80 former 17, crystal 30 and tube 50, and the con- 85 verted energy appears in transformer 58.

The energy present in transformer 44 is passed by crystal 30 and capacity 32 comprising a filter having an over-neutralized characteristic and having an input-output characteristic as shown in Figure 2e and having a reactance character- 90 65 65 70 75 80 85 90 95 100 105 110 115 120 125 130 135 140 145 150 155 160 165 170 175 180 185 190 195 200 205 210 215 220 225 230 235 240 245 250 255 260 265 converted to an amplitude modulated wave as shown in Figure 2h.

From an examination of Figure 2d and Figure 2h it can be seen that the side bands are approaching cancellation of the carrier in Figure 2d and are approaching aiding the carrier in Figure 2h. Thus, the envelope of the amplitude modulations produced by the two filters having characteristics as shown above are 180° apart and their detected output must be combined in a push-pull or series combination to reproduce the converted modulations instead of a parallel combination. This combination is effected in the diode circuit of Figure 1 by reversing the connections of one of the diode resistors 61 and 63 as shown and connecting the same in series to produce the receiver output. Unwanted amplitude modulations on the wave received which are not converted to phase modulations by the action of the two filters including crystal 30 as described herein and in my United States Patent No. 2,035,003, dated June 29, 1937, have the same or substantially the same effect on the energies passed by both filters, and consequently due to the phase displaced combination of energies in resistors 61 and 63 cancel each other more or less completely. The unwanted amplitude modulations which are converted to characteristic phase modulations have no effect in the diode detectors 59 and 60.

By an examination of the filter characteristics of Figures 2a and 2e it can be seen that when the carrier frequency drifts the relative amplitudes of the two filter outputs varies differentially. That is, as the frequency drifts lower the output of the filter of Figure 2e approaches the dip point whereas the output of the filter of Figure 2a reduces more gradually. This results in a differential action which produces differential detected energy which may be used for automatic frequency control purposes.

Turning now to the phase modulating or unmodulating method and means of the present invention, the manner in which potentials produced at 61 are used to narrow or widen the phase deviations on the wave will be described.

The phase modulator utilizes a reactance tube type of modulator comprising tube 80 operated somewhat as described in my United States application Serial No. 209,919, filed May 25, 1938. Intermediate frequency energy is applied to the input of tube 4 having tuned circuit 5 connected between its anode and cathode. Reactance tube 80 has its anode 82 and cathode 84 connected across tuned circuit 5 by connections 4' and 5' so that voltage applied to the injector grid 81 of tube 80 will vary the reactance between the electrodes 82 and 84 in a well known manner and thereby vary the tuning of circuit 5 and consequently vary the phase of the voltage in tuned circuit 5. This phase varied voltage is fed through coupling condenser 11 to amplifier tube 6 which has the primary winding 10 of transformer 17 in its plate circuit. Resistors 18 and 19 properly damp the tuned transformer 17. The elements numbered 17 to 63 described in detail hereinbefore comprise the phase modulated current converting and detecting means.

The currents or voltages resulting from the conversion and demodulation of the phase modulated wave or current appear across resistors 61 and 63 and are fed through lead 68 and radio frequency filter 69 to the injector grid 81 of the reactance tube 80. Blocking condenser 74 feeds voltage to the control grid of reactance tube 80

through phase shifting elements R1C1. Resistor 75 furnishes a direct current return for the control grid 79.

In describing the operation of the receiver of Figure 1 phase modulated current having a phase deviation of 120° will be assumed to be obtained in tube 4 and transformer 17. Normally such a degree of deviation would overload a phase modulation receiver of the crystal filter type shown here. However, by utilizing inverse feedback the detected phase modulation output at resistors 61 and 63 is caused to "unmodulate" the incoming wave in such a manner as to reduce the degree of modulation already present on that wave. Thus, if the energy fed from the detectors through lead 68 causes the reactance tube 80 to impart a phase modulation of 60° which has a polarity opposite to the 120° applied phase modulation, the effective depth of phase modulation amplified by tube 6 and fed by transformer 17 to the detecting system will be 60°. Such a depth of modulation would not overload the phase modulation converting system and detectors. Hence, for this particular illustration the modulation capabilities of the receiver have been doubled.

To obtain this unmodulation of the current in tube 4 the signal voltages supplied by resistors 61 and 63 are supplied to filter 69 and then to the grid 81 in a sense to produce in tuned circuit 5 a reactive change which will cause a phase shift of say 60° in a sense to oppose the original 120° phase shift.

If the polarity of the voltages supplied to grid 81 are of improper phase their phase can be reversed. That is, the automatic frequency control potentials and the inverse feedback potentials are in accordance with my invention maintained in the desired sense to control the frequency of the intermediate frequency wave and to, when desired, unmodulate the same.

Numerous means for obtaining the desired polarity of the control potentials in the feedback circuit to widen or narrow phase deviations may be devised. The following means are satisfactory for this purpose.

The polarity of the output of detector tubes 50 and 60 (with respect to both the AFC potentials and the inverse feedback or IFB potentials) may be reversed by grounding the cathode of diode detector 60 and making the cathode of diode detector 50 the high potential point or by grounding the cathode of diode detector 50 and making the cathode of diode detector 60 the high potential point. The gang switches S₁ and S₂ serve this purpose, that is, ground either diode and simultaneously connect the other diode to the lead running to the useful output, the automatic frequency control, and the feedback circuit. Thus by changing this connection proper polarity may be obtained for either the automatic frequency control or the intermediate frequency feedback circuits. For purposes of illustration, let us say the polarity is adjusted for the automatic frequency control operation. If, with this connection, the polarity of the intermediate feedback is wrong, the condenser C₁ in the phase shifting circuit of the reactance tube 80 may be replaced by the inductance L₁ so that the reactive effects applied to the tuned circuit 5 have an effect opposite to that produced by the capacitance.

Alternative means and methods for changing the polarity of the intermediate feedback potentials have also been illustrated. Such means may take the form of a coupling and amplifying tube 75

90, connected in circuit by switches S₃ and S₄ at contacts C to replace the direct connection between points B. A transformer 91 also serves this purpose, when connected by contacts A to 5 replace the direct connection between contacts B and B. When the coupling tube and amplifier 90 is used for reversing the feedback potentials, it may be, as illustrated in Figure 1, coupled at its input by coupling condenser 92 to contact C 10 and at its output by an additional coupling condenser 93 to the other contact C. Plate potential is supplied by impedance 94 and grid potential is supplied by impedance 95.

The polarity of the detected output may also 15 be reversed by feeding diode 60 from coupling transformer 44 and feeding diode 50 from coupling transformer 58. This interchanges the connections of the over- and under-neutralized crystal filters so that both the automatic frequency control output and the modulation output 20 are reversed.

In operation the following procedure is used 25 to adjust for proper polarity of AFC voltage and unmodulating voltage. Ganged switches S₁, S₂ are thrown up or down to set the proper polarity 30 for the AFC regardless of the unmodulating potentials. The unmodulating potentials may then be set to their proper polarity by means of 35 switches S₃, S₄ and S₅. With switches S₃, S₄ on points B, the polarity of the voltage fed to the 40 injector grid of unmodulating reactance tube 80 is the same as that fed to the AFC. With the switches on point C, amplifier 90, with coupling condensers 92 and 93 and plate resistor 94, is connected in the circuit so that the well-known 180 45 degree phase shift of an amplifier tube is imparted to the unmodulating potentials. With the switches on point A, transformer 91 is connected in the circuit and may be connected to effect 50 either zero or 180 degrees phase shift by reversing the connections to its terminals. Switch S₅ is also capable of imparting a 180 degree phase 55 shift to the polarity of the modulation which is caused by reactance tube 80. This is due to the fact that S₅ either connects in condenser C₁ to effect a leading phase angle to the feedback voltage of the reactance tube, or connects in inductance L₁ to effect a lagging phase angle to the feedback voltage. The leading phase angle 60 makes the reactance tube plate circuit appear as an inductance in parallel with tuned circuit 5 so that an increase in gain of the reactance tube causes a reduction of the total inductance in the tuned circuit. The lagging phase angle 65 makes the reactance tube appear as a capacity in parallel with the tuned circuit so that an increase in gain of the reactance tube increases the total capacity. Since a reduction of the total inductance in the tuned circuit is a tuning opposite in 70 direction to an increase in capacity, switch S₅ will therefore perform the function of reversal of the polarity of the "unmodulation" which is applied by the potentials from the output of the phase modulation detecting system.

The circuits of Figure 3 and Figure 4 show 75 alternative modifications in which double detection superheterodyne receivers are utilized. The inverse feedback potentials are applied to phase modulate the second beating oscillator by means of corrected frequency modulation in the case of Figure 3 and by means of phase modulation in the case of Figure 4.

In Figure 3 energy from antenna 100 is fed to a superheterodyne receiver, consisting of a radio frequency amplifier, first detector and high

frequency oscillator 102, a band pass filter and amplifier 103 and a second detector 104. The beating oscillator 115 produces oscillations which are frequency multiplied and limited at unit 107. The oscillator 115 has an oscillation generating 5 circuit 117 coupled by condenser 118 and grid leak and condenser 119 between its grid and anode. Potential for operation is supplied by choke 116. The reactance of circuit 117 includes or is supplemented 10 by the reactance tube 106. Reactance tube 106 is somewhat similar to the reactance tube 80 of Figure 1. In Figure 3, however, the reactance tube 106 controlled by potentials supplied at 111 is coupled to an oscillation generator comprising 15 tube 15 and circuit 117 whereas the reactance tube 80 of Figure 1 is connected to the wave relaying circuit 5. The multiplied and limited oscillations are fed to detector 104 and beat with the wave from 103. Energy at the second intermediate frequency obtained from second detector 104 is fed to the phase modulation detecting system 105. This phase modulation detector may be of any type such as, for example, the under- and over-neutralized filter type as illustrated in Figure 25 1.

The output for the detecting system in 105 is available at 110 and is also fed through frequency correcting elements 108 and 109 and filter 111 to the reactance tube 106 to modulate the 30 frequency thereof. Correction circuit 108, 109 attenuates the low audio frequencies with respect to the high audio frequencies so that the potentials applied from circuit 111 to reactance tube 106 have their amplitudes proportional to their 35 frequency. The frequency modulation of the oscillations produced in tube 115 and circuit 117 is converted into phase modulation thereof by means of condenser 109 and the resistance of potentiometer 108. The resistance of 108 is 40 made low compared to the reactance of 109 so that the voltage fed to the modulating grid of the reactance tube 106 will be directly proportional to the audio frequency of the modulating potentials supplied by the output of the phase 45 modulation detecting system. This correction converts the modulation applied to beating oscillator 115 into phase modulation. The polarity of this phase modulation is adjusted so that the heterodyned wave in the output of detector 104 50 resulting from the beat between the beating oscillator and the incoming signal has its degree of phase modulation reduced with respect to that on the incoming signal. This frequency correction causes frequency modulation oscillator 106 to 55 supply phase modulated waves to unit 107. Unit 107 contains limiters for removing concomitant amplitude modulation undesirably introduced in the process of phase modulating oscillator 115 and also contains frequency multiplying stages 60 for increasing the degree of phase modulation on the wave from oscillator 106. This oscillator energy is used as the beating oscillator for detector 104 so that the beat resulting between the incoming wave and the oscillator energy will be 65 phase modulated in the same accordance that the oscillator energy produced by 115 is modulated.

Since the potentials applied to correction circuit 108, 109 may be of such phase as to cause inverse feedback and thereby reduce the depth 70 of modulation applied to detecting system 105, this system has the same advantage as the system of Figure 1 and in addition has the possibility of being able to increase the degree of inverse feedback by frequency multiplying beating oscillator 75 1.

115. Also by using corrected frequency modulation a high degree of phase modulation is possible, so that a high degree of inverse feedback is possible and a receiver capable of handling a 5 high degree of wideband phase modulation is effected.

The elements of Figure 3, such as 100, 102, 103, 104, 105, 107 and 115 correspond with the elements of Figure 4 such as 100, 102, 103, 104, 10 105, 107 and 115. In Figure 4 the same advantage with regard to frequency multiplication (and consequent increase of the degree of inverse feedback) is present. This circuit is different from that of Figure 3 in that the inverse feedback potentials are fed to a phase modulator unit instead of to a frequency modulated oscillator. The 15 audio frequency correction circuit 108 and 109 of Figure 3 is therefore unnecessary.

In the circuit of Figure 4, the second beating oscillator 140 is also modulated as in Figure 3, but a phase modulator is used instead of a corrected frequency modulator. The beating oscillator consists of tube 140 with crystal 141 and tuned circuit 142. Link coupling 143 couples the 20 oscillator output to tuned circuit 144 which is midtapped so that two voltages 180 degrees out of phase are available at its terminals. The resistance-capacity phase shifter 145, 146 shifts the phase of the voltage fed to the control grid 25 149' of modulator tube 147 so that it is 45 degrees out of phase with the voltage supplied to it by the tuned circuit 144. The difference in phase between the voltages fed to the control grids 149' and 150' of tubes 147 and 148 is therefore 30 180 degrees plus or minus 45 degrees which is 135 degrees or 225 degrees. Either 135 or 225 degrees is the optimum phase shift for this 35 type of phase modulator in which two phase differentiated voltages are recombined in tuned circuit 151 after one of them has been amplitude modulated. More in detail, the phase displaced oscillations supplied by oscillator 140, link 143 and phase displacing circuits 144, 145 and 146 are applied to the grids of the amplifying and 40 modulating tubes 147, 148 to appear in the combined circuit 151. If we assume that these phase displaced oscillations are of constant amplitude, there will be produced in tuned circuit 151 oscillations of a phase determined by the phase 45 displaced oscillations. The resultant oscillations will have a phase which is the approximate mean of the phases of the oscillations of displaced phase, assuming they are of like amplitude. Now, if the amplitude of one of the phase displaced 50 oscillations be changed, the resultant will obviously shift in phase through an angle limited by the angular displacement of the phase displaced oscillations. To accomplish this modulation of the oscillations amplified in modulators 55 147 and 148, I control the amplification of one of the tubes, as, for example, tube 147, in accordance with the modulating potentials. This is accomplished by impressing the modulating potentials on the electrode 149. Here, since it is 60 desired to modulate or unmodulate the phase of phase modulated waves appearing in 104, I use for modulating purposes potentials derived from the output of the phase modulation source in 105. These potentials are supplied by line 65 168 to amplitude regulating resistor or potentiometer 153 and from said resistor 153 to electrode 149 by way of filter circuit 152 which removes or eliminates from the modulating potentials of a frequency greater than the modulation frequency. The circuit arrangement, per se, is such

that the modulating potentials are of the proper polarity to unmodulate or additionally modulate phase modulated waves applied to the detector 105 as desired. That is, the phase modulations on the frequency multiplied energy supplied by 5 107 to 104 for beating purposes are such as to result in intermediate frequency waves wherein the original phase deviations are increased or decreased, as desired. In the event the potentials are not of the desired polarity, expedients such 10 as described in connection with Figure 1 may be resorted to, to adjust the potentials to the desired polarity.

In Figures 3 and 4 the phase detecting system of unit 105 has been omitted for the sake of 15 clarity and simplicity. This detecting system may be as illustrated in Figure 1, or any other detecting system having the desired characteristics may be used here.

In any of the above systems cascade phase 20 modulation may be applied to increase the degree of inverse phase modulation, if desired. For instance, in the circuit of Figure 1 the energy fed through line 68 could also be fed to the injector grid of a second reactance tube which 25 was placed across a tuned amplifier stage preceding tube 4.

It will be apparent that any type of phase modulator or any type of phase modulation detecting system would be applicable to this type 30 of circuit.

I claim:

1. In means for demodulating alternating electrical current the phase of which has been varied in accordance with signals, a phase modulated 35 wave demodulator, means for applying said phase modulated current to said demodulator to produce therein potential variations characteristic of the phase variations of said current, and means for modulating the phase of said current in accordance with said potentials. 40

2. In means for demodulating alternating electrical current the phase of which has been varied through a wide range in accordance with signals, a phase modulated wave demodulator 45 operative over a range of phase modulation less than said wide range, means for applying said phase modulated current to said demodulator to produce therein potential variations characteristic of the phase variations of said current, and means for unmodulating the phase of said phase modulated current in accordance with said potentials. 50

3. Means for demodulating phase modulated electrical wave energy comprising, phase modulated wave energy detecting means, means for applying said phase modulated energy to said detecting means, means connected with said detecting means for deriving therefrom potentials characteristic of the phase deviations on said phase modulated wave energy, and means energized by said derived potentials for modulating the phase modulated wave energy to change its degree of modulation before it is applied to said detecting means. 55

4. Means for demodulating electrical wave energy phase modulated to a high degree comprising in combination, phase modulated wave energy detecting means, means for applying said phase modulated energy to said detecting means, 60 means connected with said detecting means for deriving therefrom potentials characteristic of the phase deviations on said phase modulated wave energy, and means energized by said derived potentials for unmodulating the phase modulated 70 75

wave energy to reduce its degree of modulation before it is applied to said detecting means.

5. Means for demodulating wave energy the phase of which is modulated with signals comprising, a phase modulated wave demodulator, means for impressing phase modulated waves on said demodulator, a phase modulator in said last named means, means for deriving from the output of said demodulator potentials characteristic of the phase deviations on said phase modulated energy, and means for impressing said derived potentials on said phase modulator in a sense to additionally modulate the phase modulations on said wave energy to change the degree of modulation.

6. Means for demodulating wave energy the phase of which is modulated through a wide degree in accordance with signals comprising, a phase modulated wave demodulator, means for impressing phase modulated waves of a wide degree of modulation on said demodulator, a phase modulator in said last named means, means for deriving from the output of said demodulator potentials characteristic of the phase deviations

on said phase modulated energy, and means for impressing said derived potentials on said phase modulator in a sense to unmodulate the phase modulations on said wave energy to reduce the degree of modulation.

- 30 7. In a system for demodulating wave energy the phase of which has been modulated in accordance with signals, a phase modulated wave demodulator, a local oscillator, heterodyning means connected with said local oscillator and energized by said phase modulated wave energy to produce a beat note, means for impressing said beat note on said demodulator, means for deriving from said demodulator potentials characteristic of the phase deviations on said wave energy, and potential distorting means for applying said derived potentials to said oscillator to control the frequency of oscillations thereof.

- 45 8. Means for demodulating wave energy the phase of which is modulated in accordance with signals comprising, a phase modulated wave demodulator, heterodyning means including a local oscillator and a detector for reducing the frequency of said wave energy, means for impressing said energy of reduced frequency on said demodulator, means for deriving from the output of said demodulator potentials which vary in amplitude linearly in accordance with the phase deviations on said energy of reduced frequency, and means for modulating the frequency of said local oscillator in a sense to additionally modulate the phase modulations on said wave energy to change the degree of modulation.

- 55 9. Means for demodulating wave energy the phase of which is modulated through a wide degree in accordance with signals comprising, a phase modulated wave demodulator, heterodyning means including a local oscillator and a detector for reducing the frequency of said wave energy of a wide degree of modulation, means for impressing said energy of reduced frequency on said demodulator, means for deriving from the output of said demodulator potentials which vary in amplitude linearly in accordance with the phase deviations on said energy of reduced frequency, and means for modulating the frequency of said local oscillator in a sense to unmodulate the phase modulations on said wave energy to reduce the degree of modulation.

- 70 10. In a phase modulated wave demodulating system, a phase modulated wave demodulator, a

source of local oscillations, a detector on which said phase modulated wave energy is impressed, a frequency multiplier coupling said oscillator to said detector to produce a beat note between said phase modulated wave energy and oscillations from said oscillator, means for impressing said beat note on said demodulator, means for deriving potentials from the output of said demodulator characteristic of the phase deviation on said wave energy and means for phase modulating the oscillations from said oscillator in accordance with said derived potentials.

11. Means for demodulating wave energy the phase of which is modulated in accordance with signals comprising, a phase modulated wave demodulator, heterodyning means including a local oscillator for reducing the frequency of said wave energy and impressing said energy of reduced frequency on said demodulator, a phase modulator in said last named means, means for deriving from the output of said demodulator potentials characteristic of the phase deviations on said phase modulated energy, and means for impressing said derived potentials on said phase modulator in a sense to additionally modulate the phase modulations on said wave energy of reduced frequency to change the degree of modulation thereof.

12. Phase modulated wave receiving means comprising in combination, wave relaying phase modulated wave detecting means, means including a phase controlling variable reactance for applying a phase modulated wave to said detecting means, means connected with said detecting means for deriving therefrom potentials characteristic of the phase deviations on said phase modulated wave, and means connected with said reactance and energized by said derived potentials for varying said reactance in a sense to additionally modulate the phase modulated wave applied by said relaying means to said detecting means to change its degree of modulation.

13. Receiving means as recited in claim 12 wherein, said additional modulation is in a sense to decrease the phase modulation on said wave.

14. Receiving means as recited in claim 12 wherein, said additional modulation is in a sense to increase the phase modulation on said wave.

15. Phase modulated wave receiving means comprising in combination, phase modulated wave detecting means of the balanced type, amplifying means for applying phase modulated waves to said detecting means, a reactance tube in shunt to said amplifying means, means connected with said detecting means for deriving therefrom potentials characteristic of the phase deviations on said phase modulated wave, and means for controlling the reactance of said tube in a sense to additionally modulate the phase modulated wave to reduce its degree of modulation.

16. In a system for demodulating wave energy the phase of which has been modulated to a high degree in accordance with signals, a phase modulated wave demodulator of the differential output type, amplifying means including a variable reactance connected with said demodulator and energized by said phase modulated wave energy, means for deriving from said demodulator potentials characteristic of the phase deviations on said wave energy, and means for controlling reactance of said amplifying means in accordance with said potentials to additionally modulate the phase of said wave energy.

17. The method of demodulating phase modu-

lated wave energy which includes the steps of, producing oscillatory energy, multiplying the frequency of said oscillatory energy, beating said wave energy with said oscillatory energy of multiplied frequency and controlling the phase or frequency of said oscillatory energy in accordance with the phase deviations on said wave energy.

18. The method of demodulating phase modulated wave energy which includes the steps of, 10 beating said wave energy with oscillatory energy to produce a phase modulated resultant to be demodulated, producing potentials which vary directly in accordance with the frequency of the modulations on said resultant and controlling the 15 frequency of the oscillatory energy in accordance with said produced potentials.

19. In a system for demodulating wave energy the phase of which has been modulated to a high degree in accordance with signals, a phase mod-

ulated wave demodulator, a circuit on which said wave energy is impressed, an electron discharge device having electrodes on which said wave energy is impressed in phase displaced relation to produce a reactive effect between electrodes of 5 said device, a connection between said last named electrodes and said circuit to connect said reactive effect in said circuit which is thereby tuned to the frequency of said wave energy, a phase modulated wave demodulator coupled to said circuit, means for deriving from said demodulator potentials characteristic of the phase deviations on said wave energy, and means for applying said derived potentials to an electrode of said tube to modulate its impedance and thereby control 10 the reactive effect of said circuit and phase modulate the wave energy impressed on said demodulator.

MURRAY G. CROSBY.
